UNITED STATES PATENT OFFICE.

JEHAN DE FROMENT, OF NOTRE DAME DE LOURDES, CANADA.

PYROXYLIN AUTOMATIC ELECTRIC FIRE-ALARM.

SPECIFICATION forming part of Letters Patent No. 643,491, dated February 13, 1900.

Application filed July 26, 1899. Serial No. 725,173. (No model.)

To all whom it may concern:

Be it known that I, JEHAN DE FROMENT, a subject of the Queen of Great Britain, residing at Notre Dame de Lourdes, county of Rock 5 Lake, in the Province of Manitoba and Dominion of Canada, have invented a new and Improved Automatic Alarm, of which the following is a full, clear, and exact description.

The object of the invention is to provide a 10 new and improved automatic alarm which is very simple and durable in construction, effective in operation, and more especially designed as a fire-alarm and arranged to instantly sound an alarm in a distant place or 15 actuate a sprinkling or other fire-extinguishing apparatus in case of any incipient conflagration and at the same time give the exact location of the fire.

The invention consists of novel features and 20 parts and combinations of the same, as will be fully described hereinafter and then pointed out in the claims.

A practical embodiment of my invention is represented in the accompanying drawings, 25 forming a part of this specification, in which similar characters of reference indicate corresponding parts in both the views.

Figure 1 is a side elevation of the improvement arranged as an electric fire-alarm with 30 the circuit-closer in an open position, and Fig. 2 is a side elevation of the circuit-closer in a closed position.

As illustrated in Fig. 1, an indicator or annunciator A, of any approved construction, 35 and an alarm-bell B are in a circuit having a battery C or other source of electricity, circuit-wires D D' being connected with contact-posts E E', respectively, of a controller F, shown in the form of a circuit-closer and 40 normally held inactive, as indicated in Fig. 1, by means hereinafter more fully described. The circuit-closer is provided with two members G G', carrying the contact-posts E E', respectively, and pivotally connected with each 45 other at G² with a spring H for closing these members and bringing the posts in contact with each other to close the circuit and sound the alarm B and actuate the indicator in case of a fire, as hereinafter more fully described. 50 The two members G G' are locked in an open position against the tension of the spring H by a cord I, tied around the ends of the mem-

bers opposite the contact-posts, and the said cord extends over a charge of an easily-inflammable material J, such as pyroxylin, held 55 in recesses in said members, the cord being preferably in direct contact with said material. From the material J lead a number of strings J', of like material as the charge, preferably pyroxylin, spun in very thin threads 60 and extending to various parts of a room, so that in case of a fire the threads are ignited and finally ignite the charge J, which burns the cord I, so as to release the members G G'. When this takes place, the spring H at once 65 moves the members G G' into a closed position to bring the posts E E' in contact, whereby the circuit is closed and the alarm is sounded, and the indicator announces the room or place where the fire started. It is understood 70 that any desired number of such circuit-closers may be connected with the indicator, according to the size of the building to be protected against fire.

It is understood that pyroxylin that ignites 75 at about 130° centigrade is very serviceable for the purpose, as it is very quick in action when ignited, produces a bright flame with very little heat, and hence does not set fire to its surroundings, but actuates the controller, 80 so that the alarm is sounded almost instantly and before the fire has gained any headway.

The pyroxylin used is not at all dangerous, it properly being trinitrocellulose. According to the best chemical analysis the conversion of pure cotton or cellulose may be expressed by the following formula: 85

The cord is preferably impregnated with 90 nitrate of potash.

From the foregoing it is evident that the apparatus is instantaneous—that is, works instantaneously at the least incipient conflagration—is in itself without danger, and works 95 under all circumstances or conditions.

The threads J' can be placed on walls, furniture, or floors, and whether cold or warm the apparatus will work with the same quickness.

Having thus fully described my invention, I claim as new and desire to secure by Letters Patent—

1. A thermostatic apparatus comprising an

actuated device, an operating device therefor, said operating device comprising spring-pressed members, a continuous locking-cord engaging both members and having an unbroken stretch between them, and a charge of highly-inflammable material independent of the locking-cord, said charge being held between the said members and engaging the cord.

10 2. An electric fire-alarm provided with a

circuit-closer having spring-pressed members, a cord for locking the members in an open position, a charge of pyroxylin held on said members, with the cord in contact with the charge, and threads of pyroxylin leading from said charge in different directions, as set forth.

JEHAN DE FROMENT.
